UNITED STATES PATENT OFFICE.

JOHN C. DUEBER, OF NEWPORT, KENTUCKY.

DESIGN FOR A WATCH-CASE.

SPECIFICATION forming part of Design No. 20,476, dated January 13, 1891.

Application filed December 5, 1890. Serial No. 373,728. Term of patent 14 years.

To all whom it may concern:

Be it known that I, JOHN C. DUEBER, a citizen of the United States, and a resident of Newport, county of Campbell, State of Kentucky, have invented and produced a new and original Design for Watch-Cases, of which the following is a full, clear, and exact description, reference being had to the accompanying drawing, making part of this specification.

This invention relates to a new design in watch-cases, shown in a case of full bassine form, on the front lid of which is shown a plane circular portion A, designating the center or poles of the case, from which a series of alternating grooves B and oval ribs C radiate, the grooves diverging and the ribs enlarged as they approach the central portion

of the periphery or apex of diameter of the case, decreasing and converging as they approach a similar circle or pole portion on the back or reverse lid, presenting a series of scallops, and plane ribs extending from the central portion of the front lid over the oval side or margin of the case to a similar central portion on the back or reverse lid.

What I claim is—

The design for a watch-case, as herein shown.

In testimony whereof I have hereunto set my hand this 26th day of November, A. D. 1890.

JOHN C. DUEBER.

Witnesses:

W. K. MILLER,
CHAS. R. MILLER.
